COLLAPSIBLE STAND

Gilbert M. Ellman, Chicago, Ill., assignor to Aristo-Craft Products, Chicago, Ill., a partnership

Application June 11, 1958, Serial No. 741,411

7 Claims. (Cl. 45—121)

This invention relates to collapsible stands or rests for supporting music sheets, papers, books and the like.

It is a general object of the invention to provide a new and improved stand of the type described.

Another object is to provide a new and improved music stand of light weight materials which may be readily collapsed into a compact unit convenient for carrying and storage and which may be easily unfolded for use as a sturdy support.

A more specific object is to provide a new and improved music stand of the type described including a collapsible leg structure and a foldable rest structure, the latter having one portion permanently joined to the leg structure and another portion connectable to the leg structure for holding the stand in an upright unfolded condition.

The particular embodiment of the invention chosen for illustration is intended primarily for use by musicians in bands or orchestras for supporting music sheets in front of the seated musician; it is particularly adapted for such use because it is readily collapsible into a compact unit convenient for carrying by hand or other transportation during movement from place to place. However, it will be understood the utility is not limited to that described.

The invention is illustrated in a preferred embodiment in the accompanying drawings, in which:

Fig. 1 is a front elevational view of the stand disposed in an unfolded upright position;

Fig. 2 is a side elevational view of the stand as illustrated in Fig. 1;

Fig. 3 is a front elevational view of the stand in collapsed condition; and

Fig. 4 is a side elevational view of the stand as illustrated in Fig. 3.

Referring now to the drawings in more detail, in a preferred embodiment, a stand incorporating the principles of the present invention includes a collapsible leg structure generally designated 10 and a foldable rest structure generally designated 11. The leg structure 10 comprises a first or inner inverted V-shaped leg frame 13 including a pair of separate legs 14 and 15 having lower ends spaced rather widely apart and adapted to rest on the floor and having upper ends joined as at 16 at the apex of the frame. If desired, the lower ends of legs 14 and 15 may be provided with suitable rubber-like shoes as at 17. A second or outer V-shaped leg frame 18 has separate legs 19 and 20 including upper ends which are rather widely spaced apart and lower ends joined as at 21 and adapted to rest on the floor.

Intermediate portions of the leg frames 13 and 18 are pivotally interconnected as by having each leg of the outer frame 18 pivoted on one leg of the frame 13. In the preferred embodiment illustrated, legs 19 and 20 of the outer frame 18 are pivotally connected respectively to the legs 14 and 15 of the inner frame 13 as by pivot pins 23 which may take the form of bolts, screws or rivets. At the pivots 23, legs 19 and 20 of the outer frame 18 pass outwardly of the legs 14 and 15 of the inner frame 13.

2

If desired, the pins 23 may be removably mounted, and the respective legs of the two frames may be provided with a series of holes which enable an adjustment of the pivotal interconnection to vary the effective height of the stand. Preferably, the outer frame 18 is provided with a plate or disc as illustrated at 25 suitably secured to the frame legs as at 26 and providing a support for an emblem or other indicia for identifying a particular band or orchestra.

10 The rest structure 11 is comprised of two portions, a first portion in the form of an elongated plate 27 secured adjacent opposite ends to the upper ends of the legs 19 and 20 of frame 18 as at 28. As illustrated, the second rest portion comprises a plate 30 of a length comparable to that of the plate 27 and of a substantial width in a front to rear direction as will be apparent on viewing the drawings. The second rest portion 30 is pivoted to the lower edge of the first rest portion 27 as by a pair of hinges seen at 31. Adjacent its upper edge, the rest portion 30 has a centrally located opening 33 therethrough adapted to fit over the upper end of the inner leg frame 13 when the stand is in the upright unfolded position illustrated in Figs. 1 and 2.

25 The opening 33 provides the second rest portion 30 with a hook-like means adapted to latch over the projecting end 16 of the frame 13 for securely retaining the stand in the upright position of Figs. 1 and 2. In this position, as seen in Fig. 2, the frames 13 and 18 are inclined from the vertical and cross each other at the pivotal interconnection 23, so that the leg frames provide a three point support at 17, 17 and 21. In this position of the stand, the first rest portion 27, of course, lies substantially in the plane of the outer frame 18 to which it is attached, and the second rest portion 30 extends upwardly and rearwardly from the lower edge of rest portion 27 toward the upper end of the leg frame 13. Due to the inherent weight of the stand, it will be apparent that the lower ends of the leg frames cannot pivot toward each other, and due to the latching of the rest portion 30 over the upper end of leg frame 13, the frames are prevented from pivoting in the opposite direction, so that the stand is rigidly disposed in the position illustrated to provide a sturdy support for music sheets, and the like.

30 The stand is readily collapsible from the position illustrated in Figs. 1 and 2 to the compactly folded position of Figs. 3 and 4. Collapse of the structure is effected by simultaneously pulling upwardly on the upper rest portion 30 while pivoting this portion in a counterclockwise direction as viewed in Fig. 2 to release the rest portion 30 from the upper end of frame 13. After this release, the outer frame 18 may easily be pivoted in a counterclockwise direction as viewed in Fig. 2 to dispose the outer frame 18 in the plane of the inner frame 13 in the manner illustrated in Figs. 3 and 4, with the inner frame nested 35 within the outer frame 13. Such movement disposes the rest portion 27 against lower portions of legs 14 and 15 of the inner frame 13, and the upper rest portion 30 may be pivoted to lie against the leg portions of both frames as seen in Figs. 3 and 4. Preferably, the disc or plate 25 is provided with a latch or other fastening means illustrated at 35, pivoted at 36 and adapted to releasably latch over the edge of rest portion 30 to securely retain the stand in the collapsed position illustrated. Such latch means securely holds all the parts of the stand in the position shown so that the stand may be gripped by hand 40 as at the portions 16 or 21 for carrying.

45 In the preferred embodiment illustrated, the leg frames 13 and 18 are comprised of tubular aluminum or similar lightweight materials, and the rest portions 27 and 30 may be comprised of light-weight metal material or of pressed fiberboard or similar materials so that the entire weight 50 of the stand is negligible and readily portable.

The foregoing detailed description is given for clearness of understanding only and no unnecessary limitations should be understood therefrom as modifications will be obvious to those skilled in the art.

I claim:

1. A collapsible stand, comprising: an inner frame having a lower end adapted to rest on the floor, a hollow outer frame having a lower end adapted to rest on the floor and an intermediate portion pivotally connected to an intermediate portion of the inner frame, a rest including a front portion secured to the upper end of one frame substantially parallel thereto and a rear portion hinged on the lower edge of the front portion, and releasable means for detachably connecting the upper rear end of the rear portion to the upper end of the other frame to releasably retain the stand in upright position with the frames inclined from the vertical and crossing at their pivotal interconnection, and with said rear rest portion inclined upwardly and rearwardly from the front rest portion so that the latter forms a retaining ledge for the former.

2. A collapsible stand, comprising: an inner frame having a lower end adapted to rest on the floor, a hollow outer frame having a lower end adapted to rest on the floor and an intermediate portion pivotally connected to an intermediate portion of the inner frame for swinging movement thereon into the plane of the inner frame, a rest including a front portion secured to the upper end of the outer frame substantially parallel thereto and a rear portion hinged on the lower edge of the front portion, releasable means for detachably connecting the upper end of the rear portion to the upper end of the inner frame to releasably retain the stand in upright position with the frames inclined from the vertical and crossing at their pivotal interconnection, and with said rear rest portion inclined upwardly and rearwardly from the front rest portion toward the inner frame so that the front portion forms a retaining ledge for the rear portion, release of said releasable connecting means enabling pivotal movement of the outer frame in a direction to move the upper end downwardly and the lower end upwardly to position the outer frame in the plane of the inner frame and position the rear rest portion in the plane of the front rest portion, and latch means for releasably securing the frames and rest portions in the collapsed condition last described.

3. A collapsible stand, comprising: a first pair of legs rigidly connected together and having lower ends spaced apart and adapted to rest on the floor, a second pair of legs rigidly connected together, and having lower ends adapted to rest on the floor, means pivotally connecting each leg of one pair to one leg of the other pair, a rest including a front portion secured to one pair of legs above the pivotal interconnection of the legs generally parallel thereto and a rear portion pivoted to the front portion, and means for detachably connecting said rear portion to the other pair of legs above said pivotal interconnection to retain the stand in upright position with the pairs of legs inclined from the vertical and crossing at said pivotal interconnection, and with said rear rest portion inclined rearwardly and upwardly from the front rest portion to said other legs so that the front rest portion forms a retaining ledge for the rear rest portion.

4. A collapsible stand, comprising: a first leg frame including a pair of legs having upper ends rigidly joined and lower ends spaced apart and adapted to rest on the floor, a second leg frame including a pair of legs having lower ends rigidly joined and adapted to rest on the floor, means pivotally connecting intermediate portions of the frames, a rest including a plate pivoted on the upper leg portions of the second frame and having an opening there-

through adjacent its upper edge to fit over the upper ends of the legs of the first frame to retain the stand in upright position with the frames inclined from the vertical and crossing at the pivotal interconnection of the frames, and with said plate inclined rearwardly and upwardly to the first frame.

5. A collapsible music stand, comprising: an outer V-shaped frame, an inner inverted V-shaped frame, means pivotally interconnecting intermediate portions of the frames with the legs of the outer frame outwardly of the legs of the inner frame at the pivotal interconnection, a rest including a first plate secured to upper ends of the outer frame and a second plate hinged to the first plate, said second plate having an opening therethrough adjacent its upper edge to fit over the apex of the inner frame to retain the stand in upright position with the frames inclined and crossing at the pivotal interconnection, release of the second plate from said inner frame enabling swinging movement of the outer frame into the plane of the inner frame, and a latch for releasably securing the outer frame to the second plate to retain the stand in collapsed condition.

6. A collapsible stand, comprising: an outer V-shaped frame, an inner V-shaped frame, means pivotally interconnecting intermediate portions of the frames with the legs of the outer frame outwardly of the legs of the inner frame at the pivotal interconnection so that the frames are swingable relative to each other between a collapsed condition with the inner frame nested in the outer frame in a common plane therewith and an unfolded condition with the frames inclined from the vertical and crossing at the pivotal interconnection and with one frame inverted, a rest comprising a plate having one edge pivotally connected to the upper end of one frame when the frames are unfolded, and means for detachably connecting the opposite edge of said plate to the upper end of the other frame to retain the frames in the unfolded condition, release of said connecting means enabling collapse of the frames and movement of said plate to a position parallel and adjacent the frames for storage.

7. A collapsible music stand, comprising: an outer V-shaped frame, an inner inverted V-shaped frame, means pivotally interconnecting intermediate portions of the frames with the legs of the outer frame outwardly of the legs of the inner frame at the pivotal interconnection, a rest including a front plate secured to upper ends of the outer frame generally parallel thereto and a rear plate hinged to the lower edge of the front plate, said rear plate having an opening therethrough adjacent its upper edge to fit over the apex of the inner frame to retain the stand in upright position with the frames inclined and crossing at the pivotal interconnection and with the rear plate inclined upwardly and rearwardly from the front plate, release of the rear plate from said inner frame enabling swinging movement of the outer frame into the plane of the inner frame and said rear plate into the plane of the front plate, and latch means for releasably securing the frames and plates in the collapsed condition last described.
